[57] CLAIM

The ornamental design for a wall sconce, as shown and described.

DESCRIPTION

FIG. 1 is a perspective view of a first embodiment thereof;

FIG. 2 is a top plan view of a first embodiment thereof;

FIG. 3 is a front elevational view of a first embodiment thereof;

FIG. 4 is a side elevational view of a first embodiment thereof;

FIG. 5 is a rear elevational view of a first embodiment thereof;

FIG. 6 is a bottom plan view of a first embodiment thereof.

FIG. 7 is a perspective view of a second embodiment thereof;

FIG. 8 is a top plan view of a second embodiment thereof;

FIG. 9 is a front elevational view of a second embodiment thereof;

FIG. 10 is a side elevational view of a second embodiment thereof;

FIG. 11 is a rear elevational view of a second embodiment thereof;

FIG. 12 is a bottom plan view of a second embodiment thereof; and,

FIG. 13 is a side elevational view of a third embodiment thereof.

The perforations are understood to be continuous over the side of the housing in FIG. 13.

It is understood that the third embodiment differs from the second embodiment only by the addition of the perforations on each of the side panels.
